UNITED STATES PATENT OFFICE

2,541,029

RECLINING ACCESSORY FOR BATHTUBS

Walter Charles Calvin Burton, Columbus, Ohio

Application February 2, 1948, Serial No. 5,811

1 Claim. (Cl. 4—162)

1 This invention relates to a bathing and reclining accessory.

An object of this invention is to provide a bathing and reclining accessory which may be mounted in a bath tub whereby the user may take a steam bath without becoming chilled, the device including a padding engageable within a tub, and a flexible cover which may be secured to the edges of the padding by interengageable fastening means.

Another object of this invention is to provide a device of this kind which can be used within a tub, or if desired may be used as a beach or picnic accessory and provide an enclosed padding or mat outdoors. The covering being removable, the padding may be used either with or without the covering when the device is used outdoors. The device may also be used in a tub without the covering where it is desired to rest or recline in hot water or the like.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a plan view of a bathing and reclining accessory constructed according to an embodiment of this invention.

Figure 2 is a plan view of the device with the cover removed.

Figure 3 is a plan view of the mat or padding.

Figure 4 is a plan view of the cover.

Figure 5 is a plan view of the cushion.

Figure 6 is a longitudinal section taken substantially on the line 6—6 of Figure 3.

Figure 7 is a transverse section taken substantially on the line 7—7 of Figure 3.

Figure 8 is a longitudinal section of a modified form of pad or mat.

Figure 9 is a transverse section of the modified form of mat or pad shown in Figure 8.

Referring to the drawings, the numeral 10 designates generally a conventional bath tub having a well 11. In order to provide a means whereby a person may obtain a steam bath or the like in the well 11 of the tub, I have provided a mat or padding, generally designated as 12 which is adapted to engage in the well 11 of the tub. The mat or padding 12 is formed of a longitudinally disposed main pad 14 having longitudinally ex-

tending side or wing pads 15 extending therefrom. The main pad 14 is formed of an upper flexible cover 18 and a lower flexible member 16. Each wing or side member 15 is formed of upper 5 and lower flexible cover members 17 and 18 and the covers 17 and 18 may be formed integral with the covers 13 and 16, respectively, and the junction between the central member 14 and the wing members 15 may be defined by a line of 10 stitching 19.

The mat or pad 12 also includes a head pad member 20 which is formed of upper and lower flexible walls 21 and 22 which may be formed integral with the walls 13 and 16, respectively, and the inner end or junction between the head member 20 and the bottom pad member 14 may be defined by a transverse line of stitching 23. Each wing 15 has secured thereto an arm rest pad member 24 which is secured to the inner wall 17 20 of the wing and the arm rest members 24 are adapted when the device is in the well of a tub to engage on the upper side of a pillow or cushion member 25. The pillow or cushion member 25 is disposed adjacent the head end of the central 25 pad member 14 and being free of the mat or pad 12, the cushion 25 may be shifted to any desired or convenient position.

The marginal edges of the wing members 15 have an interengageable fastening means 26 secured thereto and the fastening means 26 extends about the foot end of the central pad 14 as indicated at 27 so that a single slider may be used for securing the cover to the wings and the base or bottom pad member 14. The head pad 20 is 30 also provided with interengageable fasteners 28 for engagement with complementary fasteners carried by the cover as will be hereinafter described.

A flexible cover 29 which may be formed of 40 waterproof fabric, vulcanized fabric or the like is adapted to engage over the padding member 12 when disposed in the well of a tub. The cover 29 has a configuration similar to the configuration of the well of a tub being elongated with a 45 rounded head end and the cover 29 is provided with interengageable fastening means 30 on the outer edges thereof which are complementary to the fastening means 26 and 27. The fastening means 30 terminates as indicated at 31 at substantially the neck portion of the covering. The upper rounded head end 32 of the covering 29 has fastening means 33 secured to the outer edge thereof which are complementary to the fastening means 28.

The cover 29 is split through the longitudinal

center thereof as indicated at 34 and complementary interengageable fastening means 35 are secured to the edges of the split central portion 34 so that this split may be closed and preferably the slider for closing the split portion of the cover 29 is engageable from the inside of the cover. The cover 29 is formed with a rounded opening 36 at the head end thereof through which the head of the user may be extended. The cover 29 is also formed with a pair of split portions 37 inwardly from the head opening 36 and the slits 37 include interengageable fastening means 38 so that these slits may, if desired, be closed. When the slits 37 are open the arms of the user may be extended through these slits.

Referring now to Figures 8 and 9, there is disclosed an inflatable bathing and reclining device which is similar in every detail to the construction shown in Figures 1 to 7, with the exception that the padding between the walls of the device has been removed and the flexible material of which the device is formed is air-tight, being formed of rubberized fabric, rubber or the like. The main longitudinal pad 14a is formed of upper and lower flexible walls 13a and 16a which are formed of air-tight material and the head member 20a is formed of flexible walls 21a and 22a and the walls 21a and 22a may be formed integral with the walls 13a and 16a. A pair of wings or side members 15a are carried by the lengthwise edges of the member 14a and the wing members 15a are also of inflatable construction and communicate with the interior of the main body member 14a so that the entire pad may be inflated through a single air valve 39. The wing members 15a also include arm rest members 24a which communicate with the interior of the wing members 15a and receive air under pressure from the interior of the wing members. It will be understood that the marginal edges of the structure shown in Figures 8 and 9 will include interengageable fastening means so that a cover similar to the cover 29 may be detachably secured to the inflated pad or mat.

In the use of this device the lower pad or mat 12 may be placed in the well 11 of a tub with the head member 28 oppositely from the water discharge nozzle usually present at one end of the tub. The cover 29 may be secured about the marginal edge portions thereof to the marginal

portions of the base pad 12 with the central slit 34 left open so that a person may enter between the cover and the pad. When a person is reclining on the pad 12 the central slit may be closed by pulling the slider from the foot end of the device, thereby snugly closing the cover about the neck, with only the head of the user projecting therefrom.

This device may also be used as a beach pad or a picnic accessory and the cover 29 may optionally be used when the device is used outdoors.

I claim:

A reclining accessory for disposing in a bathtub comprising a pad member formed of an elongated impervious pad, a pair of elongated wings extending from the lengthwise edges of said pad, an impervious head pad extending from one end of said first pad and formed with divergent side edges, an arm rest pad carried by the inner side of each wing adjacent said head pad, an impervious flexible cover having a length slightly greater than the length of said first pad and having a width substantially the same as the width of said first pad, said cover having a lengthwise slit and a head opening, means securing the edges of said slit together, and correlated fastening means carried by said cover about the marginal edges thereof and the outer edges of said wings, said head and the foot end of said first pad, said cover when in applied position holding said wings and head pad in upwardly inclined position.

WALTER CHARLES CALVIN BURTON.
